UNITED STATES PATENT OFFICE.

GERHARDT G. M. F. HARTMANN, OF WHITE PLAINS, NEW YORK.

ORNAMENTAL BEADING FOR JEWELRY.

Application filed December 23, 1920. Serial No. 433,564.

To all whom it may concern:

Be it known that I, GERHARDT G. M. F. HARTMANN, a citizen of the United States, and a resident of White Plains, in the county 5 of Westchester and State of New York, have invented a new and Improved Ornamental Beading for Jewelry, of which the following is a full, clear, and exact description.

This invention relates to ornamental bead work, and has particular reference to the provision of supporting frames and structures for beading which may be used in connection with necklaces and other similar devices.

An object of the invention is to provide a simple, economically manufactured, and strong framework on which ornamental beading may be mounted in accordance with any particular design, so that this framework can be used as one of a plurality of units, if desired, in a necklace or similar device.

Another object of the invention resides in the particular construction and arrangement 25 of parts hereinafter described and claimed and shown in the accompanying drawings.

The invention is illustrated in the drawings, of which—

Figure 1 is an elevation of a necklace provided with a plurality of beading units made in accordance with my invention;

Figure 2 is a section taken on the line 2—2 of Figure 1;

Figure 3 is an elevation of the portion 35 shown in Figure 2;

Figure 4 is an elevation of a modified form of necklace embodying my invention;

Figure 5 is a further modification of the framework;

Figure 6 is a section taken on the line 6—6 of Figure 5; and

Figure 7 is a detail sectional view of the framework units shown in Figure 4.

As shown in the drawings, the invention is embodied in the form of a necklace of ribbon 1 intermediate the length of which a plurality of units of beadwork, such as are represented by the letter A, are inserted. Similar units may be disposed at the ends 50 of the ribbon in the form of a pendant, such as represented by the letter B in Fig. 1.

Each of these beading units or frames comprises an outer rectangular frame portion formed of any suitable wire, such as gold or

silver wire. This outer wire frame has a pair 55 of parallelly disposed portions 2 and 3 extending the length of the unit and a pair of integral, transversely extending supporting members 4 and 5. Beads 6 may be strung on the members 2 and 3 in accordance with 60 any suitable design. These beads may be of any size or color to give the required ornamental effect. The transversely extending members 4 and 5 may, as shown in Figures 1 and 5, be adapted to be connected to the 65 ribbon 1. The members 2, 3, 4 and 5 are formed of one single piece of wire. In order to properly and laterally space the longitudinally extending members 2 and 3, a plurality of spacing plates 7 and 8 are disposed 70 across between the members 2 and 3 at opposite ends of the frame unit. The ends of these plates 7 and 8 are suitably pierced to receive the members 2 and 3 and are disposed between adjacent beads on the unit. Depending upon the particular shape and design of 75 the unit, a plurality of auxiliary, longitudinally extending bead-supporting members, such as 9, 10 and 11 shown in Figure 3, may be provided on which beads may be strung. 80 These auxiliary, longitudinally extending members may be tied to and between the reinforcing plates 7 and 8 above mentioned.

As shown in Figure 3, the members 9 and 10 at each end are connected to the plates 7 and 8, whereas the auxiliary member 11 extends below the plate 8 and is adapted to support an ornamental ring 12 which has a loop 13 thereon by which it is supported from the lower end of the member 11. This 90 ring may be formed in any ornamental design and, as shown in Figure 3, is provided with a gold or silver tube 14 surrounding the ring 12. An additional ornamental bead, such as 15, may be supported in the center 95 of the ring 12.

As shown in Figure 3, the cross members 4 and 5 of the outer frame of the beading unit are provided with loops, such as 16, 17 and 18. The loops 16 and 17 are adapted to 100 engage with connections such as 19 seen in Fig. 1, joining the unit, as shown in the lower part of Fig. 1, with the lower end of the ribbon 1. The loop 18 above mentioned forms a lateral support for the lower portion 105 of the auxiliary, longitudinally extending wire or member 11. This loop also forms a spacing means for a bead, such as 20, which

is strung on the lower end of member 11. The loop 21, as shown in Figure 3, is bent back on itself and twisted around the member 11 to further position the bead 20 on the member 11.

As shown in Figure 5, the auxiliary members 22 and 23 are not strung with beads but support a solid plate 24 of any suitable ornamental material, such as glass, which is provided, as shown in Figure 6, with longitudinally extended grooves 25 in which the members 22 and 23 are adapted to lie. As shown in this figure, the auxiliary members 22 and 23 are integrally connected and are tied at their lower ends to the lower plate 8.

Above and below the reenforcing plates 7 and 8 and disposed on the wires 2 and 3 of the outer frame of the unit, a plurality of larger beads, such as 26, are disposed and rigidly held on the wires 2 and 3 by engagement with the plates 7 and 8 and by reason of a twist or bend, such as 27, given to the wires 2 and 3 on the opposite side of these larger beads 26.

As shown in Figure 7, which is a detail representation of the type of unit shown in Figure 4, the central auxiliary bead-supporting wire, such as 28, extends both below and above the main frame wires, which are tied thereto by being twisted therearound, as shown at 29 in Figure 7, and this central auxiliary member 28 is connected to links, such as 30, which co-operate with other beads or with the ribbon 1. A larger bead, such as 32, can be inserted between the twisted connection 29 and a loop 33. As shown in Figure 4, the lower unit on this necklace is provided with a pendant, such as 34. In Figure 3 it will be noticed that ornamental tubing, such as 35, can be strung on the frame members, such as 2 and 3, instead of beads. Whichever arrangement is used being entirely within the discretion of the person making the design.

It will be seen, therefore, from a consideration of the figures, taken in connection with the above description, that I have provided a frame unit which may be made in many different designs and provided with arrangements of beads and ornamental articles thereon which essentially comprises a plurality of definitely spaced, parallelly extending wires or rods which are so inter-linked, as above described, as to form, when the beads are mounted thereon, a highly ornamental, economically manufactured and strong unit. These units can be arranged in the form of a necklace of ribbon or other material. The invention, it is clearly understood, is not, nevertheless, limited to the use of these units merely with bracelets or necklaces but can be used with other ornamental devices. The particular manner of tying the frame wires to each other and reinforcing them as described presents an ex-

ceptionally strong and rigid unit which is flat and cannot be easily distorted from its proper shape.

What I claim is:

1. A frame for beading for jewelry and ornamental articles, which comprises a main frame member formed of longitudinally extending members and transversely extending members integrally connected, a plurality of beads and ornamental articles on the longitudinally extending members, said transversely extending members reinforcing and spacing the longitudinally extending members, and a plurality of transverse plates extending between the longitudinal members intermediate the ends of the main frame to strengthen the frame.

2. A frame for beading for jewelry and ornamental articles, which comprises a main frame member formed of longitudinally extending members and transversely extending members integrally connected, a plurality of beads and ornamental articles on the longitudinally extending members, said transversely extending members reinforcing and spacing the longitudinally extending members, a plurality of transverse plates extending between the longitudinal members intermediate the ends of the main frame to strengthen the frame, and a plurality of auxiliary, longitudinally extending ornamental articles supporting members disposed between and supported by the reinforcing plates.

3. A frame for beading for jewelry and ornamental articles, which comprises a main frame member formed of longitudinally extending members and transversely extending members integrally connected, a plurality of beads and ornamental articles on the longitudinally extending members, said transversely extending members reinforcing and spacing the longitudinally extending members, a plurality of transverse plates extending between the longitudinal members intermediate the ends of the main frame to strengthen the frame, and a plurality of auxiliary, longitudinally extending ornamental articles supporting members disposed and supported between the reenforcing plates, one of said auxiliary, longitudinally extending members extending at each end beyond the main frame to connect with other units and supports.

4. A frame for beading for jewelry and ornamental articles, which comprises a main frame member formed of longitudinally extending members and transversely extending members integrally connected, a plurality of beads and ornamental articles on the longitudinally extending members, said transversely extending members reinforcing and spacing the longitudinally extending members, a plurality of transverse plates extending between the longitudinal members

intermediate the ends of the main frame to strengthen the frame, and a plurality of auxiliary, longitudinally extending, ornamental article supporting members disposed 5 and supported between the reenforcing plates, one of said auxiliary, longitudinally extending members extending at each end beyond the main frame to connect with other units and supports, the transversely 10 extending members of the main frame connected to the auxiliary member which extends beyond the main frame at the point of intersection.

5. A frame for beading for jewelry and ornamental articles, which comprises a plurality of longitudinally and transversely ex-

tending wires integrally connected in the form of a rectangular frame, a plurality of beads and ornamental articles on the longitudinal wires, a plurality of auxiliary 20 spacing and reenforcing plates extending between the longitudinal wires intermediate their length, and a plurality of auxiliary longitudinal wires supported between the spacing plates to receive beads and ornamental articles, the ends of the longitudinal frame wires being bent and integrally connected to hold the beads firmly in position thereon and to form a loop adapted to connect the frame with other units and supporting members. 25

GERHARDT G. M. F. HARTMANN.
